AUTOMATIC MULTIPLE TIME SWITCH

John C. Gillette, Dayton, Ohio, assignor to Cap Products Inc., Dayton, Ohio, a corporation of Ohio

Application March 6, 1939, Serial No. 259,937

11 Claims. (Cl. 200—38)

The present invention relates to automatic time switches and particularly to those switches which employ a plurality of pairs of longitudinal arms carrying contact points at their extremities.

The primary object of the present invention is to provide an automatic time switch capable of making and breaking circuits, carrying large currents, and having a minimum number of parts and of simple design. This object is attained in brief by dividing the load current into two or more portions, and passing each current portion through separate circuits which are individually made and broken by a multi-contact time switch. The contacts of the latter are controlled by arms which are operated by a clock mechanism, and the various movements of the arms are brought out by levers secured to a timing dial which is provided with a special gear mechanism to introduce a slow and accurate time adjustment.

Another object of the invention is to provide a time switch of the multi-contact type, in which the contacts are automatically wiped during operation so as to present clean contact surfaces at all times, which offer the minimum resistance to current flow and minimum heating effects. This object is attained in brief by pivotally mounting one end of the contact-carrying arms on the switch and during a period immediately before the contacts open, moving each pair of arms as a unit on their respective pivots, which causes one arm to move slightly in the longitudinal direction with respect to the other arm. This longitudinal movement causes the surface of one contact to slide over the surface of the other contact.

A still further object is to provide a switch capable of making and breaking a plurality of circuits and necessitating a plurality of contacts for each circuit, said switch being so constructed that the break is made practically instantaneously at each set of contacts without drawing an arc, whereby excessive "pitting" is avoided. This object is attained in brief by securing the corresponding arm of each set of contacts together and providing a spring common to the arms which are secured together for moving the contacts carried by said arms away from the opposing contacts at a high rate of speed.

Another object is to provide a time switch for controlling a plurality of circuits, necessitating a set of contacts per circuit, and in which the arms which carry the contacts are provided with a self-aligning feature by which the contacts are adapted to be simultaneously closed and a firm seating of the contacts over their entire area is obtained. This object is attained in brief by

providing a circuit-closing spring for each set of contacts, the function of the spring being to close the contacts to which it is assigned and without interference with or by the springs which close the other contacts.

Other objects and features will be apparent as the specification is perused in connection with the accompanying drawings, in which—

Figure 1 represents a front plan view of a box with its cover in open position, the box containing the improved time switch;

Figure 2 is a plan view, looking at the rear of the switch, with the box in section;

Figure 3 is an enlarged plan view, looking at the back of the front panel of the switch and the motor, and all of the gears being removed and each of the shafts in section;

Figure 4 is an enlarged elevational view of the improved switch removed from the box;

Figure 5 shows a vertical section taken through the switch, while

Figure 6 is a view taken along line 6—6 in Figure 5, but twice enlarged;

Figure 7 is a fragmentary view of the lower contacts and arms showing the manner in which flexibility and self-adjustment is provided between the arms to assure a firm and simultaneous closure of both contacts;

Figures 8, 9 and 10 are fragmentary plan views showing different positions assumed by the contact-carrying arms and contact-closing lever during the make, wiping and break operations of the contacts;

Figure 11 is a fragmentary view, in perspective, of the gear mechanism which operates the time dial, showing the latter partly in section;

Figure 12 is a fragmentary view showing a portion of the contact-carrying arms having one of the contacts formed with a partially concave surface;

Figure 13 is an enlarged fragmentary view, in elevation, of a modified form of the improved switch removed from the box. In this figure, the motor and the gearing have been removed;

Figure 14 is a fragmentary view of the lower contacts and arms of the modified form of switch shown in Figure 13. This figure, as in the case of Figure 7, is intended to illustrate the manner in which flexibility and self-adjustment are provided between the arms to insure a firm and simultaneous closure of all the contacts.

Referring to the drawings in detail, particularly Figures 1 and 5, the switch proper includes two pairs of arms 1, 2 and 3, 4, of which only 55 the uppermost pair 1, 2 can be seen in Figure 1.

The arms 1, 3 (Figure 5) are pivotally mounted on a rod 5, which extends through a front panel member 6 of insulating material and is secured to a back panel member 7 in any suitable manner (not shown). Likewise, the arms 2, 4 (Figure 5) are pivotally mounted on a rod 8 which passes through the front panel member 6 and is also secured to the back panel member 7 in any suitable manner (not shown). These arms take the form preferably of a rectangular cross section 10 and are made of a hard insulating material such as ebonite, etc. The panels 6 and 7 are preferably made of sheet ebonite or similar insulating material.

At their ends opposite the pivots 5, 8, the front arms 1, 2 carry a pair of contacts 9, 10 (Figure 1), and the lower arms 3, 4 carry the corresponding contacts 11, 12 (Figure 4). These contacts are preferably constituted of silver and of a thickness that permits the arms to maintain 20 a substantially parallel position when the contacts are closed. This parallel arrangement is shown in Figures 1, 8 and 9.

The upper panel 6 has secured thereto, as by the screws 13, a terminal board 14 of ebonite 25 which carries a pair of relatively large hollow terminals 15 secured to the terminal board 14 by the screw bolts 17. Heavy wires 18 (Figure 4) are taken from the bolts 17 to each of the contacts 9, 10. The connection is conveniently 30 made at the arms through a cap terminal 19. Conductors 20 are carried from the terminals 15 through the sides of the box 21 which contains the switch.

The lower panel 7 is secured to the top surface of a metal plate 22 by means of the screws 23 and 24, also the screws 13, the panel and metal plate being arranged in coextensive relation. The lower edge of the panel 7 and the plate 22, as seen in Figure 1, carries a terminal 35 block 25 of ebonite, to which they are secured by the joiner plates 26. The block 25 has mounted thereon two outer terminals 27 and an intermediate terminal 28, all of fairly large size. Heavy conductors 29 are taken from the outer terminals 27, and a similar conductor 30 is connected to the intermediate terminal 28. The two terminals 27 are connected through heavy wires 31 to the contacts 11, 12 (Figure 4), the connections being conveniently made through metal 40 cap terminals 32.

The metal plate 22 is separated from a back plate 33 by a number of spacers 34 to form a compartment within which a system of gears is located, which obtain their actuation from an electrical motor 35. The plate 22 also carries on its underside, as seen more clearly in Figure 3, a spring-operated latch which is controlled by levers secured to a time dial 36 and is operated periodically in any suitable manner, for example, by a clock mechanism driven by the motor 35.

As shown more particularly in Figure 5, a rod 37 passes sidewise through the arms 1 and 3 and through an opening in the panel 6, this rod being fixedly secured to the arm 1 and extending to a position just inside of the under surface of the plate 22. It is preferred that the opening in the bar 3, which receives the rod 37 shall be somewhat larger than the rod so as to leave a clearance, as indicated at 38. A spring 39 is secured between the inner end of the rod 37 and a lug 40 on the underside of the plate 22. As will be seen more clearly from Figure 3, the rod 37 extends through the arms 1, 3 at positions

5 remote from the pivot 5. From the description given up to this point, it is obvious that a pressure on the top of either of the bars 1, 3 will cause both arms to move downwardly on their pivots 5 against the tension of the spring 39.

The lower arm 4 is provided with a rod 41 which fits tightly in the arm and extends as far as the underside of the plate 22, where it is connected by a tension spring 42 to a lug 43 secured to the plate 22. The other lower arm 2 is also provided with a rod 44 which projects through an opening in the arm 4, considerably larger than the rod, as indicated at 45, and terminates just beyond the inner surface of the plate 22. A spring 46 is connected between the inner end of the rod 43 and a lug 47 on the plate 22.

As seen more clearly in Figure 3, the plate 22 and the overlapping panel 7 are provided with openings 48 to permit a vertical movement of the rods 37, 41 and 43. The plate is also provided with a rectangular cut-out portion 49 which is in line with a slot 50 formed in the panel 7 to permit the leads 31 which pass through the plate and panel to move in a vertical direction, as the arms 3 and 4 are operated in a manner which will be described hereinafter.

In addition to the springs 39, 42 and 46, the underside of the plate 22 carries a latch 51 which is pivoted at 52 and is biased by a spring 53 which tends to move the upper portion of the latch to the left. This portion is provided with a tooth 54, the lower surface of which is flat and extends perpendicularly to the leg of the latch and the upper surface is of arcuate configuration, as indicated at 55. The tooth 54 is adapted to cooperate with a pin 56 which extends through a large opening 57 in the plate 22 and the panel 7 into the arm 4, to which it is secured, as indicated in Figure 7. The upper surface of this pin is preferably filed flat in order to firmly engage the lower surface of the tooth 54.

The pivot 52 of the lever 51 is carried through the plate 22 and the panel 7 to a contact-closing lever 58 positioned on the front side of the front panel 6. The latter is provided with an arcuate cutaway portion indicated at 59 so as to permit the lever 58 to project beyond the upper edge of the panel, as can be seen in Figures 8, 9 and 10.

The time dial 36, which determines the time at which the switch will close and open or vice versa, is marked on its front face with divisions indicating hourly and fifteen minute intervals 55 for twenty-four hours. This dial carries a contact-closing trigger 60 which projects outwardly from the front face of the dial. The trigger is positioned on a bearing sleeve located at the under surface of the dial and on a shaft, both of which are hereinafter described. The dial also carries a lever 61 which is termed a reset trigger, since it serves to trigger the arms through a reset position to the open contact position. The reset trigger is positioned at the underside of the dial, similar to the contact-closing trigger 60 and extends inwardly toward the panel 7, as shown in Figures 4 and 5.

As the dial revolves clockwise, by the actuation of the motor 35 which will also be described presently, the trigger 60 will move the contact-closing lever 58 slightly to the left. This operation serves to rotate the latch 51 on its pivot 52 and, therefore, causes the tooth 54 to slide away from the pin 56, permitting the lower arm 4 to move upwardly by the urge of the spring 42. The

other lower arm 2 will also move simultaneously with the arm 4 under these conditions due to the fact that this arm is coupled with the arm 4 through the rod 43 and will be urged upwardly by its own spring 46. It is apparent that, as the tooth 54 is withdrawn from the pin 56, when the latch 51 is rotated, the lower surface of the pin 56 will ride the arcuate surface 55 of the tooth 54.

As a preliminary condition to opening the contacts, assuming that they have been closed, the two pairs of arms 1, 2 and 3, 4 are rotated downwardly on their pivots to a so-called "reset" position. This resetting operation is produced by the rotating effect of the reset trigger 61 which bears down on a metal plate 62 secured to the upper side of the arm 3. The lefthand edge (as shown in Figures 8, 9 and 10) of the plate 62 is undercut so as to provide a sharp disengaging effect between the trigger 61 and the plate.

In order to facilitate the proper setting of the reset trigger 61 with respect to the dial so as to bring about the reset operation with great time accuracy, a vertical white line 63 (Figure 8) is drawn transversely of the black ebonite arm 1 to indicate the position that the reset trigger assumes when the reset operation is initiated.

It will be understood that, even if the contacts 9, 10, 11 and 12 were initially partially spherical, as illustrated in Figures 4, 8, 9 and 10, they would tend to flatten after continued use so that it is necessary that all parts of the contacts touch one another. Indeed, as seen in Figure 12, the lower contacts 10 and 12 may be provided with a concave surface so as to fit the convex surface of the upper contacts 9, 11.

The rotor of the motor is connected through a series of gears to drive a large main gear 74 (Figure 11). The latter gear is carried on a shaft 75, but is not keyed thereto and instead is secured to the shaft by a spring device described presently. The gear 74 has a countersunk portion into which fits a washer 76. The shaft 75 has securely attached thereto a pinion 77 which abuts the washer 76. The lefthand end of the shaft, as shown in Figure 5, is provided with a nut 78 firmly secured to the shaft; and between the nut and the gear 74, there is positioned a spring washer 79 held under compression by the nut 78.

It is apparent that, if a force were applied to cause the shaft 75 to move slightly to the right (as seen in Figure 5), the spring washer 79 will force the gear 74 against the lefthand face of the pinion 77, causing the gear 49 to drive the shaft 75. On the other hand, inasmuch as the gear is attached to the shaft 75 only through the frictional effect exerted by the washer 79, the shaft can be turned without rotating the gear if sufficient rotational effect were exercised. The manner in which the force tends to move the shaft along its axis in order frictionally to tighten the gear 74 on the shaft, and the force which is capable of turning the pinion without rotating the gear 74 will be pointed out when the remainder of the gear mechanism has been described.

There is a long multi-shouldered sleeve 80 which extends through an opening in the plate 22 and is permitted to idle on the shaft 75. The right hand end of the sleeve is provided with screw threads for receiving the threaded opening of a nut 81 knurled on its periphery. There is a multi-shouldered sleeve 82 surrounding that portion of the sleeve 80 which is of the smallest dia-

5 ter and which, in turn, carries on its shoulders the time dial 36, the circuit closing trigger 60 and the reset trigger 61. If the nut 81 were not tightened, these triggers and the dial are free to rotate on the shoulders of the sleeve 82, but are prevented from moving off the shoulders by an offset end (not shown) formed at the extreme lefthand end of the sleeve.

10 The portion of the triggers 60, 61, which is immediately adjacent to the shaft 75, has a configuration similar to a flat washer so that the triggers and the dial can be tightened on the sleeve 82 by an axial force acting on these triggers in a direction toward the nut 56. In other words, the nut can draw up the two triggers and the dial against its under surface. For this purpose, there is provided a spacing cylinder 83 which contacts with one of the shoulders on the sleeve 80 and also with the flat washer-like surface of the trigger 60.

15 It is therefore apparent that, as the nut 81 is tightened, it draws up on the sleeve 80 which exerts a compressional force against the spacer cylinder 83 which, in turn, forces the two triggers and the dial against the righthand shoulder of the sleeve 82. The latter is preferably spaced away from the nut 81 by a washer which permits the nut to be turned readily. As the nut is loosened, the dial and the two triggers are free to rotate on the sleeve 82 independently of one another.

20 The shaft 75 is carried through the entire length of the sleeve 80 and terminates in a screw-threaded end 85, carrying a knurled nut 86. It is apparent that, as this nut is rotated, the shaft 75 is likewise rotated, causing the pinion 77 to be rotated against the frictional effect of the nut 78 and the spring washer 79, and without turning the large gear 74. This pinion 77 meshes with 25 a large gear 87 (Figure 11), carried on a shaft 88 secured to the plate 22, and the shaft carries a pinion 89. The latter drives a gear 90 which is firmly secured to the lefthand shoulder of the sleeve 80. Assuming that the nut 81 has been 30 tightened on the sleeve 80 so that the triggers 60, 61 and the dial 36 are likewise tightened, any rotation of the nut 86 will turn the pinion 77, and through the gears 87, 89 and 90 will 35 rotate the sleeve 80, causing the dial and the two triggers firmly secured thereto to be rotated.

40 In Figure 14, I have shown an improved switch in which a third pair of contacts and operating arms have been added, all controlled by the same dial and motor mechanism. This construction is in general similar to that shown and described 45 in connection with the earlier figures and for that reason, corresponding reference characters have been employed to designate similar parts. The additional parts include a panel 98 and an extra set of arms 99, 100, carrying contacts 101, 102, respectively. These contacts are brought out 50 through a pair of wires 103 to terminals 104, which are mounted on a separate terminal board 105.

55 As seen in Figure 14, the third arm 100 is carried on the end of a rod 106 which passes loosely through the arms 2, 4 to the underside of the plate 22. A spring 107 is connected between the inner end of the rod 106 and a lug (not shown) 60 on the underside of the plate 22. It is apparent 65 that all three arms 4, 2, 100 operate in unison about their respective pivots to close the contacts when the lever 58 is tripped by the trigger 60. The same latch 51 (Figure 3) operates to 70 control the arm 100 as well as the arms 2, 4 and,

of course, the same reset mechanism is also employed. By providing openings in the arms 2, 4 (Figure 14), which are greater in diameter than the rod 106, the arm 108 permits its contact to align itself with the corresponding upper contact and to cause a simultaneous closing of the circuit with the circuits of the remaining pairs of contacts.

It will be understood that I desire to comprehend within my invention such modifications as come within the scope of the claims and the invention.

Having thus fully described my invention, what I claim as new and desire to secure by Letters Patent is:

1. A time switch comprising a plurality of pairs to rigid coextensive parallelly disposed arms A, B, said arms being rotatably mounted on separate axes at one end on the switch and carrying at their opposite ends contacts for making and breaking circuits, spring-operated means for simultaneously rotating arm A of each pair away from arm B of each pair to open the contacts, spring-operated means for simultaneously rotating arm B of each pair toward arm A of each pair simultaneously to close the contacts, and automatic means for preventing the operation of said last-mentioned means until after a predetermined length of time.

2. A switch comprising a plurality of pairs of parallelly disposed rigid coextensive arms, said arms being pivotally mounted at one end on the switch and carrying at the opposite ends contacts for making and breaking circuits, means for maintaining the arms in a closed contact position, means for moving all of the arms as a unit and in parallel relation about their pivots to a reset position, whereby the arms of each pair move longitudinally with respect to one another and a wiping action takes place at the contact surfaces, and means for moving the arms relatively to one another to open the contacts.

3. An automatic time switch comprising a plurality of pairs of parallelly disposed rigid coextensive arms, said arms being pivotally mounted at one end on the switch and carrying at the opposite ends contacts for making and breaking circuits, means for maintaining the arms in a closed contact position, time-operated means for moving all of said arms as a unit and in parallel relation about their pivots to a reset position, whereby the arms of each pair are moved longitudinally with respect to one another and a wiping action takes place at the contact surfaces, and spring-operated means for moving the arms relatively to one another to open the contacts.

4. A switch comprising a plurality of pairs of rigid coextensive parallelly disposed arms, said arms being pivotally mounted at one end on the switch and carrying at the opposite ends contacts for making and breaking circuits, means for simultaneously mainaining the arms of each pair in an open contact position, means for simultaneously moving the arms of each pair into a closed contact position, and means for simultaneously resetting the arms of each pair while maintaining a parallel relation of the arms ready to be moved into the open contact position by said first-mentioned means.

5. An automatic time switch comprising a pair of rigid coextensive parallelly disposed arms, said arms being pivotally mounted at one end on the switch and carrying at the opposite ends contacts for making and breaking circuits, spring-

operated means for simultaneously maintaining the arms of each pair in an open contact position, time-operated means for simultaneously moving the arms of each pair into a closed contact position, and time-operated means for simultaneously resetting the arms of each pair while maintaining a parallel relation of the arms ready to be moved into open contact position by said first-mentioned means.

6. An automatic time switch comprising a plurality of pairs of parallelly disposed coextensive arms, said arms being pivotally mounted at one end on the switch and carrying at the opposite ends contacts for making and breaking circuits, spring-operated means for simultaneously maintaining the arms of each pair in an open contact position, time-operated means for simultaneously moving the arms of each pair into a closed contact position, and time-operated means for simultaneously resetting the arms of each pair ready to be moved into the open contact position by said first-mentioned means, said resetting means serving to rotate the arms of each pair together as a unit about their pivots whereby the arms of each pair move longitudinally with respect to one another and a wiping action takes place at the contact surfaces.

7. A switch comprising a plurality of pairs of rigid coextensive arms A, B, said arms being pivotally mounted at one end and on the switch and carrying at their opposite ends contacts for making and breaking the circuits, said contacts being normally open, said arms A being arranged in parallel alignment and operated simultaneously, said arms B being arranged in parallel alignment and operated simultaneously, and means for moving arms B as a group toward arms A during which period the arms B flexibly adjust themselves to provide a firm closure between contacts.

8. A time switch comprising a plurality of pairs of rigid coextensive arms A, B, said arms being pivotally mounted at one end on the switch and carrying at their opposite ends contacts for making and breaking circuits, spring-operated means for simultaneously moving the arms A away from the arms B to open the contacts, spring-operated means for simultaneously moving the arms B toward their respective arms A to close the contacts, the arms A being operated simultaneously, and the arms B being flexibly secured together, whereby the arms A, B align themselves to provide a simultaneous seating of all the contacts when the switch is closed.

9. A switch comprising a plurality of pairs of rigid arms A, B, arranged in parallel coextensive relation, said arms being pivoted on the switch at one end and carrying contacts at the other end for opening and closing circuits, a rod connected to the arms A and a spring secured to said rod to swing the arms A about their pivots into open circuit position, a separate rod connected to each of said arms B, a spring secured to each of said last-mentioned rods to swing each arm B about its pivot into closed circuit position, and means for controlling the operation of the contact-opening and contact-closing springs.

10. A switch comprising a plurality of pairs of arms A, B arranged in parallel coextensive relation, said arms being pivoted on the switch at one end and carrying contacts at the other end for opening and closing circuits, a rod connected to the arms A and a spring secured to said rod to swing the arms A about their pivots into open circuit position, a separate rod con-

2,240,000

nected to each of said arms B, said last-mentioned rods passing through openings in the arms B, said openings being of greater size than the rod except at the arm to which the rod is secured, whereby flexibility is introduced between the rods and the arms, and a spring secured to the end of each rod opposite from the end which is secured to the arm to swing each arm B about its pivot into closed circuit position, the flexibility between the rod and arm serving to provide a firm closure at all of the contacts, and means for controlling the operation of the contact-opening and contact-closing springs.

11. An automatic time switch including a plurality of pairs of rigid coextensive arms A, B, 15 said arms being pivotally secured at one end to

the switch and carrying at the opposite ends contacts for making and breaking circuits, spring-operated means for simultaneously moving the arm B of each pair toward arm A of each pair for closing the contacts, time-operated means for simultaneously moving arms A, B of each pair as a unit on both pivots of each pair to a second position, means for simultaneously locking the arm B of each pair in a second position, spring-operated means for simultaneously returning arm A of each pair to its initial position, and time-operated means for releasing said locking means whereby arm B of each pair is permitted to be moved by its spring-operated means to its contact-closing position.

JOHN C. GILLETTE.
